[57] CLAIM

The ornamental design for a putter head, as shown.

DESCRIPTION

FIG. 1 is a front view of the putter head showing my new design;

FIG. 2 is a rear view thereof;

FIG. 3 is a side elevation of the putter head taken from the left hand side of FIG. 1;

FIG. 4 is a side elevation taken from the opposite side;

FIG. 5 is a top plan view of the putter head;

FIG. 6 is an underneath plan thereof; and

FIG. 7 is a cross-section through the putter head and taken as indicated by the line X—X of FIG. 5.
